FIG. 2.

UNITED STATES PATENT OFFICE.

JOHN SAYER AND GEORGE G. DENT, OF FLAGSTAFF, ARIZONA.

VISE.

1,079,883.

Specification of Letters Patent. Patented Nov. 25, 1913.

Application filed December 28, 1910. Serial No. 599,711.

To all whom it may concern:

Be it known that we, JOHN SAYER and GEORGE G. DENT, citizens of the United States, residing at Flagstaff, in the county 5 of Coconino and State of Arizona, have invented new and useful Improvements in Vises, of which the following is a specification.

The present invention provides a work 10 holding appliance designed chiefly for carpenters and joiners use for holding work to a bench or other support, said appliance being in the nature of a vise and embodying a fixed jaw and a movable jaw, the latter 15 being operated by mechanism which admits of quick action of the jaw when adapting the vise to the particular work in hand.

The invention aims to supply a vise of 20 novel structure and to combine therewith peculiar actuating means for the movable jaw, whereby the same may be quickly adapted to the work and moved to secure the same and instantly released when required.

25 The invention consists of the novel features, details of construction and combination of parts, which hereinafter will be more particularly set forth, illustrated in the accompanying drawings, and pointed out in 30 the appended claims.

Referring to the drawings, forming a part of the application, Figure 1 is a vertical central longitudinal section of a vise embodying the invention, showing the operating 35 shaft in full lines. Fig. 2 is a top plan view of the movable jaw and operating shaft, a portion of the jaw being broken away. Fig. 3 is a view of the fixed jaw inverted. Fig. 4 is a transverse section on the 40 line 4—4 of Fig. 1. Fig. 5 is a cross section of the operating shaft and shanks of the jaws, showing the screwthreaded portion of the operating shaft in engagement with one set of teeth. Fig. 6 is a sectional view similar 45 to Fig. 5, showing the screwthreaded portion of the operating shaft in engagement with the other set of teeth. Fig. 7 is a sectional view similar to Figs. 5 and 6, showing the operating shaft lowered to 50 throw the screwthread portion thereof out of engagement with both sets of teeth. Fig. 8 is a diagrammatical view, showing the relation of the screwthread portion of the operating shaft and the two sets of teeth.

55 The vise is constructed so that when fitted

to a bench the fixed jaw will come about flush with the top and the front of the bench, this being desirable in the formation of a vise designed for carpenters and wood joiners. The fixed jaw 1 has a shank 2 which 60 is provided along opposite edges with guides 3 and apertured ears to receive the bolts or fastenings by means of which the vise is secured to the bench or like support. The jaw 1 and shank 2 may be of one piece and 65 the shank is approximately half round in transverse section so as to extend over the operating screw shaft. Two sets of teeth 4 and 5 are formed upon the lower or inner side of the shank 2 and extend lengthwise 70 thereof in parallel relation and are located upon opposite sides of a medial line and equidistant therefrom. The teeth are formed upon ribs so as to stand out from the inner or lower wall of the shank 2. The teeth 75 form segments of threads and coöperate with the thread of the screw shaft to move the sliding jaw. The teeth 4 have a different arrangement from the teeth 5 so that one set of teeth only is in engagement with 80 the thread of the screw shaft at a time.

The movable jaw 6 has a shank 7, which is hollow and the complement of the shank 2 so as to form therewith a cylindrical casting for inclosing the operating screw shaft 85 when the parts are assembled. The shank 7 has outer flanges 8 along its upper longitudinal edges to enter the guides 3 and hold the movable jaw and shank in place and direct the jaw 6 in its sliding movements. The shank 7 is half round in cross section and the space inclosed thereby is closed at its 90 ends by pieces 9 and 10, which support the operating shaft 11. The front end piece 10 has an elongated opening 12 for the passage of the operating shaft 11. The end piece 9 has an opening 13 in its inner wall to receive the rear end of the shaft 11. The jaws and their shanks may be formed in any 95 manner. The operating shaft 11 is mounted in the end pieces 9 and 10 to admit of its having a limited vertical and lateral play and has an enlarged portion 14 near its rear end of circular outline. A portion of the enlargement 14 is threaded, as indicated at 15, and a portion is left plain, as indicated at 16, and has an opening 17 to receive a projection 18 located at the rear end of the shank 7 adjacent to the wall 9. The projection 18 acts in the capacity of a lift and 110

a stop. As a lift the projection 18 moves the shaft 11 upward to bring the thread 15 of the part 14 into position to engage with the teeth 4 and 5, whereby upon turning the shaft 11 the movable jaw 6 is drawn inward toward the fixed jaw so as to clamp the work placed between the two jaws. As a stop the projection 18 engages an end of the opening 17 to prevent backward turning of the shaft 11 when the projection 18 is lying within the opening 17. Upon turning the operating shaft 11 to the right the enlargement 14 rides upon the projection 18 and is elevated thereby to bring the thread 15 into engagement with one or the other sets of teeth 4 or 5 so that a continued rotation of the shaft will cause the thread 15 to coöperate with the teeth and move the jaw 6 toward the jaw 1 and clamp the work in position between the two jaws.

When the shaft 11 reaches a position in its rotation to bring the opening 17 of the part 14 in register with the projection 18 the latter enters the opening 17, thereby permitting the shaft to drop a distance to permit the thread 15 clearing the teeth 4 and 5 so that the jaw 6 may be freely moved outward or inward to accommodate the distance between the two jaws to the size of the work to be gripped. After the movable jaw has been properly adjusted the shaft 11 is turned and the part 16 riding upon the projection 18 is lifted to bring the thread 15 into engagement with the teeth 4 or 5 and a continued rotation of the shaft causes the thread 15 to coöperate with the teeth engaged thereby to move the jaw so as to clamp the work. The operating shaft may be provided with a single or a multiple thread according to the required pitch and the distance to which the jaw 6 is to be moved by a single revolution of the shaft. The teeth 4 and 5 are thread segments having a pitch to match the threads 15 of the shaft 11. The relative arrangement of the thread segments 4 and 5 is such that the arcuate threads of one segment and out of register—less than the width of one thread—with the corresponding threads of the other segment, so the threads of the screw 15 will never strike those of both the segments edge-to-edge, but will with certainty slip into engagement. This takes place when the shaft 11 is turned to the right and is elevated by the cam portion 17 riding on the cam portion 18, the threads 15 slipping into engagement with the registering arcuate threads of one or the other thread segments 4 or 5. This operation insures positive engagement of the threaded portion 15 of the operating shaft with a set of teeth connected with the fixed jaw so that the sliding jaw may be moved in a positive manner to effect a gripping of the work. The operating shaft 11 is mounted in the

wall 10 so as to prevent relative longitudinal movement of the shaft and jaw. A handle 19 is fitted to the projecting end of the shaft 11 to enable effective application of force for turning the shaft when the vise is in operation.

From the foregoing description, taken in connection with the accompanying drawings, the advantages of the construction and of the method of operation will be readily apparent to those skilled in the art to which the invention appertains, and while we have described the principle of operation of the invention, together with the device which we now consider to be the embodiment thereof, we desire to have it understood that the device shown is merely illustrative, and that such changes may be made when desired as are within the scope of the claims appended hereto.

Having thus described the invention what is claimed as new, is:—

1. In a vise comprising a fixed jaw and a movable jaw, an operating screw, and two fixed thread segments having a relative arrangement, with the arcuate threads of one segment out of register—less than the width of one thread—with the corresponding threads of the other segment so that the threads of the operating screw will never strike those of both the segments edge-to-edge but will with certainty slip into engagement.

2. In a vise comprising a fixed jaw and a movable jaw the combination of an operating screw mounted to have both a vertical and a lateral movement, means for elevating the screw and holding the same in elevated position during a revolution, and two fixed thread segments arranged upon opposite sides of a vertical plane passing through the axis of the operating screw, the relative arrangement being such that the arcuate threads of one segment are out of register—less than the width of one thread—with the corresponding threads of the other segment to prevent the matching of the threads of the operating screw with both the segments at the same time when said operating screw is elevated.

3. The herein described vise comprising a fixed jaw having a shank formed upon its inner side with longitudinal ribs which are transversely spaced, each of the ribs having arcuate threads, the threads of one segment being out of register with the corresponding threads of the other segment, a movable jaw provided with a shank having portions engaging the shank of the fixed jaw to form guide means, a shaft mounted in the movable jaw and having a limited relative lateral play and having a screwthread to match with the threads of the segments but adapted to engage with one only at the same time, said shaft having an enlarged portion hav-

ing a part formed with the before-mentioned screwthread and the remaining portion plain and formed with an opening having one side inclined, and a projection carried by the shank of the movable jaw to enter the opening of the enlarged portion of the shaft to admit of the screwthread of said shaft clearing the before mentioned segments, said shaft being elevated when turned to bring its screwthread into match-

ing engagement with one or the other of the said segments.

In testimony whereof we affix our signatures in presence of two witnesses.

JOHN SAYER.
GEORGE G. DENT.
